MANUALLY OPERATED ROTOR OAR FOR
BOATS

Anthony Graci, Bronx, N. Y.

Application June 11, 1949, Serial No. 99,559

13 Claims. (Cl. 115—23)

This invention relates to new and useful improvements in boats, as those of the ordinary row-boat sizes, and, more particularly, the aim is to provide a novel and valuable type of manually operated propulsion and steering means for a boat of the kind indicated or of other appropriate class which, by virtue of the unique advantages afforded by the new propulsion and steering means, may be employed for providing what is aptly designated as a rotor-oar water-borne craft.

According to the present invention, the manually operable propulsion and steering means proposed is characterized by the combination of a pair of bearings suitably factory inbuilt into the boat or arranged for easy attachment to the sides of a boat hull near the gunwales thereof; an athwart-extending shaft which at a central portion along its length is shaped to incorporate a pair of cranks at 180° angular displacement one from another, said shaft near each of its outer ends having fixed thereon a collar or equivalent and said shaft at its opposite end portions outwardly extended beyond said collars being axially movably journalled in said bearings; a pair of outboard paddle groups with each such groups having a hub journalled on one of the two last-named end portions of the shaft, the paddles of each wheel being oar-like and at the outer ends of arms radiating spider-fashion from the wheel's hub; with each hub at its outer side carrying one of the two complementary members of a clutch and with the other member of each clutch splined or keyed on the shaft outward of the associated clutch member adjacent to a hub; and a pair of identical minor assemblies each comprising a shiftable member incorporating a fork, ring or the like for straddling or embracing the shaft at a point therealong between one of said collars and the adjacent one of said hubs, a spring means for coacting with the similar spring means of the other of said minor assemblies for equalizingly or balancingly acting on both said shiftable members and for normally maintaining both clutches effective, thereby to render negligible the muscular effort required to move the shaft slightly axially in one direction or the other for then temporarily disabling one clutch or the other and so for steering in one direction or the other; with the last-named spring means in association with further spring means for normally maintaining both clutches effective, for straight ahead propulsion.

Because of these provisions, there is made practicable a relatively simple and inexpensive yet

2 rugged and delicately manually controllable propulsion and steering means for a boat, and even for a standard size and type of row-boat, wherein there is attainable a high speed of propulsion at relatively small muscular effort while affording an ideal exercise for the healthful development of arm, leg and torso muscles; wherein steering is particularly easily and readily effected; and wherein various other advantages are present as will be pointed out or become apparent herein-after.

For further comprehension of the invention, and of the objects and advantages thereof, reference will be had to the following description and accompanying drawing, and to the appended claims in which the various novel features of the invention are more particularly set forth.

In the accompanying drawings forming a material part of this disclosure:

20 Fig. 1 is a side elevational view of a boat formed with a propulsion means in accordance with the present invention.

Fig. 2 is a plan view of Fig. 1.

Fig. 3 is an enlarged partial transverse vertical sectional view taken on the line 3—3 of Fig. 2.

Fig. 4 is a sectional view taken on the line 4—4 of Fig. 3.

Fig. 5 is a reduced partial vertical sectional view taken substantially on the line 5—5 of Fig. 3.

30 Fig. 6 is a view similar to a portion of Fig. 3, but illustrating a modification of the present invention.

The manually operable oars, according to the first form of the invention shown in Figs. 1 to 5, are shown applied to a row-boat 10, having an outer sheathed gunwale 11 at each side and interiorly fitted with the usual bow seat 12, stern seat 14 and midship seat 15.

Transverse to the boat 10 and along a line with 40 in convenient hand hold reach of a person on the seat 15 in ordinary double oar rowing position, a shaft 17 is extended, with the two crank formations 18 and 19 thereof, these the two cranks already mentioned, having at their intermediate or 45 handle portions a circular path of swing appropriate to the seated location of said person, with the latter facing forward or toward the bow carrying the seat 12.

Bearings 20 are provided for rotatively and 50 axially slidably supporting the shaft 17. The bearings 20 are engaged over the tops of the gunwales 11 at opposite sides of the row-boat 10 slightly forward of the midship seat 15, as shown in Fig. 2. The bearings 20 are secured in position on the gunwales 11 by removable bolts 21

held in position by winged nuts 22. All parts of the propelling mechanism of the present invention are supported by the bearings 20 so that when the bolts 21 are removed the bearings 20 and all the mechanism supported thereby can be lifted clear of the row-boat 10.

The ends of the shaft 17 are slidably and rotatively extended through hubs 23 comprised of inner hub portions 23^a and mating outer hub portions 23^b. The bearings 20 have separate top portions 24 removably secured in position by removable bolts 25. The inner hub portions 23^a are formed with integral bearing portions 26 which are rotatively but non-slidably retained in the bearings 20 by the removable top portions 24.

The adjacent faces of the hub portions 23^a and 23^b are formed with matching semi-circular recesses 27 which form holes which extend radially of the hub portion and which open to the periphery thereof to have the inner ends of oar stems 28 mounted therein. The holes formed by the recesses 27 are somewhat smaller in diameter than the diameter of the oar stems 28 so as to securely clamp the oar stems 28 in position in the holes when the hub portions are securely clamped together by nut and bolt assemblies 29.

The oar stems 28 extend radially from the hubs 23 as shown in Fig. 1, and have mounted on the outer ends thereof paddles 30. The oar stems 28 are of a length so that the paddles 30 will have a path of circular sweep to be successively dipped into the water below the water line 31, see Fig. 1, as the shaft 17 is rotated.

The outer faces of the outer hub portions 23^b are integrally formed with reduced clutch portions 32 formed with clutch teeth 33 of any known configuration. Slidably mounted on the outer ends of the shaft 17 beyond the hubs 23 there are clutch discs 34 formed with clutch teeth 35 matching the clutch teeth 33 of the clutch portions 32. The outer faces of the clutch discs 34 are formed with reduced end portions 36 slidably received in tubular housings 37.

The tubular housings 37 are formed of opposed sections releasably secured together by screws 38, see Fig. 4. The outer ends of the sections forming the tubular housings 37 are closed by semi-circular wall portions 39 which engage opposed flat surfaces 40 milled into the ends of the shaft 17, as shown in Fig. 4. The engagement of the semi-circular wall portions 39 with the opposed flat surfaces 40 serves to non-rotatively and non-slidably secure the housings 37 to the shaft 17 so that when the shaft is rotated the housings will rotate therewith.

Means is provided for slidably but non-rotatively connecting the clutch discs 34 to the housings 37 so that those clutch discs 34 will rotate with the housings when the shaft 17 is rotated. That means comprises pins 41 which extend laterally from diametrically opposite sides of the reduced end portions 36 of the clutch discs 34 and which are slidably extended through complementary elongated slots 42 formed in the opposed sections of the tubular housings 37. Coil springs 43 of the expansion type are located in the tubular housings 37 and operate between the adjacent faces of the reduced end portions 36 of the clutch discs 34 and the semi-circular wall portions 39 of the tubular housings 37.

The coil springs 43 function to urge the clutch discs 34 inward relative to the tubular housings 37 and toward the clutch portions 32 to retain the clutch teeth 33 and 35 engaged so that the

hubs 23 and the oars carried thereby will be rotated when the shaft 17 is rotated.

Equalizing devices are provided for urging the shaft 17 into a neutral position with relation to the bearings 20 in which the clutch teeth 33 and 35 at each end of the shaft will be engaged, as shown in Fig. 3, so that the two hubs 23 will be turned in unison as the shaft 17 is turned. The equalizing devices are comprised of equalizing levers 44 which are pivotally supported intermediate of their ends upon brackets 45 which extend laterally inward from the bearings 20, by means of pivot pins 46. The top ends of the equalizing levers 44 are bifurcated and have their tines 47 extended vertically along opposite sides of the shaft 17 inward of the bearings 20. Cup-shaped members 48 are secured to the shaft 17 inward of the equalizing levers 44, by means of pins 49. The cup-shaped members 48 are secured to the shaft 17 at suitable locations to engage between the tines 47, as clearly shown in Figs. 2 and 3.

Contraction springs 50 have their ends securely attached to the bottom ends of the equalizing levers 44 and their other ends securely attached to the bottom ends of downward extensions 51 formed on the bearings 20. The contraction springs 50 are of equal strength and somewhat stronger than the springs 43 so as to pivot the equalizing levers 44 into positions in which the tines 47 will be engaged against the outer faces of the cup-shaped members 48. Thus, the contraction springs 50 function to urge the shaft 17 into a centrally located position with relation to the bearings 20 in which the ratchet teeth 33 and 35 at each end of the shaft 17 will be engaged.

The operation of the boat constructed in accordance with the present invention is as follows:

With the shaft 17 retained in the centrally located position, shown in Figs. 2 and 3, by the contraction springs 50, the shaft 17 can be rotated in one direction or the other by gripping the crank formations 18 and 19 to similarly turn the hubs 23 and the oars carried thereby to propel the row-boat 10 either in a forward or a rearward direction, depending upon the direction of rotation of the shaft 17.

Should it be desired to turn the row-boat in one direction or the other, this is simply accomplished by pushing the shaft 17 in the direction in which it is desired to turn while simultaneously rotating the shaft.

This will load the equalizing spring 50 at the end of the shaft 17 in which it has been pushed and free the spring 50 at the other end of the shaft. As the shaft 17 was pushed in the direction in which it was desired to turn, the shaft 17 moved axially relative to the hubs 23 which are retained stationary by reason of their rotative engagement with the bearings 20. However, at the end of the shaft 17 in the direction in which it was pushed, the tubular housing 37 is moved away from the respective hub 23 and the respective clutch disc 34, which is urged toward that hub 23 by the expansion spring 43, until the inner ends of the slots 42 contact the pins 41. When that contact occurs the clutch disc 34 will move with the tubular housing 37 away from the respective hub 23 separating the clutch teeth 33 and 35 at that side. This separation of the clutch teeth 33 and 35 will leave the hub 23 on that side of the row-boat free, which is the near side of the turn which is to be executed.

At the other end of the shaft 17, on the outside of the turn which is to be executed, the reverse action takes place. That is, the shaft 17 carries the tubular housing 37, at that other end, with it toward the respective hub 23. That action loads the respective spring 43 and presses the adjacent clutch disc 34 more firmly toward the clutch portion 32 causing the clutch teeth 33 and 35 at that end of the shaft to be more firmly engaged. Therefore, as the shaft 17 is turned with it in its axially shifted position, the hub 23 on the outside of the turn to be executed will be turned independently of the hub 23 on the inside of the turn causing the row-boat to be turned as long as the shaft 17 is rotated and held in its axially shifted position. When the force holding the shaft 17 in its axially shifted position is relaxed, the contraction springs 50 will urge the shaft 17 back to its centrally located position in which the ratchet teeth 33 and 35 at each end of the shaft will be in engagement so that rotations of the shaft 17 will again rotate both of the hubs 23 in unison for forward or rearward propelling of the row-boat 18.

In the modification of the invention shown in Fig. 6, the tubular housing 37' is of one-piece construction and is slipped over the end of the shaft 17' and the adjacent reduced end portion 36 of the clutch disc. The tubular housing 37' is fixedly and non-rotatively secured to the shaft 17' by set screws 60 threaded through diametrically opposite sides of the closed end of the tubular housing to be tightened against the shaft 17'. If desired, the end of the shaft 17' could be formed with holes to receive the ends of the set screws 60.

The inner end of the tubular housing is formed with the elongated slots 42 extended parallel to the length of the shaft 17' and pins 41', in the form of bolts, are passed through the slots 42 and threaded into receiving holes 51 formed in the reduced end portion 36 so as to slidably but non-rotatively connect the clutch disc to the tubular housing 37'. Removal of the bolts 41' and loosening of the set screws 60 will permit the tubular housing 37' to be slipped off the end of the shaft 17'.

In other respects this modification of the invention is similar to the first form and like reference numerals are used to identify like parts in all of the views.

In the forms of the invention illustrated and described both the springs 43 and 50 are used to maintain the shaft 17 in a neutral position; however, it is appreciated that the rowing mechanism of the present invention could be effectively used with either the springs 43 or the springs 50.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. A manually operable propulsion and steering mechanism for a boat having a seat for a person to operate said mechanism, said mechanism comprising a transverse shaft, bearings for securing to the boat at opposite sides thereof and supporting said shaft to be moved axially, the shaft having near the middle point of its length a pair of crank portions oppositely offset from the general line of extension of the main portions of

the shaft, said crank portions spaced in the direction of length of the shaft for grasp of each crank portion by a different hand of the person, a pair of propulsion instrumentalities each incorporating a hub-structure and a plurality of outwardly radiating oars carrying paddle formations at their outer ends, each of said instrumentalities being at a different one of the two sides of the boat and outboard relative thereto, a pair of clutches each having the two complementary members thereof on said shaft outboard relative to the hub-structure at that side of the boat, in each clutch the inner one of said members being fixed relative to the adjacent hub-structure, means rotatively connecting the outer member of each clutch to the shaft for rotation therewith and also for endwise movement with said shaft relative to its respective inner clutch member, and a plurality of springs for normally maintaining the members of both clutches in engagement to render both clutches normally effective, said shaft being axially movable for disabling the clutch at the starboard or port side of the boat and at the same time permitting the clutch at the other side of the boat to remain effective.

2. A manually operable propulsion and steering mechanism for a boat having a seat for a person to operate said mechanism, said mechanism comprising a transverse shaft, bearings for securing to the boat at opposite sides thereof and supporting said shaft to be moved axially, the shaft having near the middle point of its length a pair of crank portions oppositely offset from the general line of extension of the main portions of the shaft, said crank portions spaced in the direction of length of the shaft for grasp of each crank portion by a different hand of the person, a pair of propulsion instrumentalities each incorporating a hub-structure and a plurality of outwardly radiating oars carrying paddle formations at their outer ends, each of said instrumentalities being at a different one of the two sides of the boat and outboard relative thereto, a pair of clutches each having the two complementary members thereof on said shaft outboard relative to the hub-structure at that side of the boat, in each clutch the inner one of said members being fixed relative to the adjacent hub-structure, means rotatively connecting the outer member of each clutch to the shaft for rotation therewith and also for endwise movement with said shaft relative to its respective inner clutch member, and a plurality of springs for normally maintaining the members of both clutches in engagement to render both clutches normally effective, said shaft being axially movable for disabling the clutch at the starboard or port side of the boat at the same time permitting the clutch at the other side of the boat to remain effective, said hub-structures being split and each of such split portions having radially extending registering half round recesses, the root ends of said oars being seated in and girthed by said recesses, and clamping means for coupling said split portions thereby to grip and anchor said root ends.

3. A manually operable propulsion and steering mechanism for a boat having a seat for a person to operate said mechanism, said mechanism comprising a transverse shaft, bearings for securing to the boat at opposite sides thereof and supporting said shaft to be moved axially, the shaft having near the middle point of its length a pair of crank portions oppositely offset from the general line of extension of the main

portions of the shaft, said crank portions spaced in the direction of length of the shaft for grasp of each crank portion by a different hand of the person, a pair of propulsion instrumentalities each incorporating a hub-structure and a plurality of outwardly radiating oars carrying paddle formations at their outer ends, each of said instrumentalities being at a different one of the two sides of the boat and outboard relative thereto, a pair of clutches each having the two complementary members thereof on said shaft outboard relative to the hub-structure at that side of the boat, in each clutch the inner one of said members being fixed relative to the adjacent hub-structure, means rotatively connecting the outer member of each clutch to the shaft for rotation therewith and also for endwise movement with said shaft relative to its respective inner clutch member, a plurality of springs for normally maintaining the members of both clutches in engagement to render both clutches normally effective, said shaft being axially movable for disabling the clutch at the starboard or port side of the boat and at the same time permitting the clutch at the other side of the boat to remain effective, and means including a pair of elements each fixed on the shaft near a different end thereof at a point inboard relative to said hub-structures for moving said shaft to a centrally located position with relation to said bearings.

4. A manually operable propulsion and steering mechanism for a boat having a seat for a person to operate said mechanism, said mechanism comprising a transverse shaft, bearings for securing to the boat at opposite sides thereof and supporting said shaft to be moved axially, the shaft having near the middle point of its length a pair of crank portions oppositely offset from the general line of extension of the main portions of the shaft, said crank portions spaced in the direction of length of the shaft for grasp of each crank portion by a different hand of the person, a pair of propulsion instrumentalities each incorporating a hub-structure and a plurality of outwardly radiating oars carrying paddle formations at their outer ends, each of said instrumentalities being at a different one of the two sides of the boat and outboard relative thereto, a pair of clutches each having the two complementary members thereof on said shaft outboard relative to the hub-structure at that side of the boat, in each clutch the inner one of said members being fixed relative to the adjacent hub-structure, means rotatively connecting the outer member of each clutch to the shaft for rotation therewith and also for endwise movement with said shaft relative to its respective inner clutch member, a plurality of springs for normally maintaining the members of both clutches in engagement to render both clutches normally effective, said shaft being axially movable for disabling the clutch at the starboard or port side of the boat and at the same time permitting the clutch at the other side of the boat to remain effective, and means including a pair of elements each fixed on the shaft near a different end thereof at a point inboard relative to said hub-structures for moving said shaft to a centrally located position with relation to said bearings, said last-named means further including, for coaction with each of said elements, a pivotally mounted equalizing lever, and springs acting on each of said levers, said last-named springs being arranged individually to yield according as

the shaft is endwise moved in one direction or the other.

5. A manually operable propulsion and steering mechanism for a boat having a seat for a person to operate said mechanism, comprising a transverse shaft, bearings for securing to the boat at opposite sides thereof and supporting said shaft to be moved axially, the shaft having near the middle point of its length a pair of crank portions oppositely offset from the general line of extension of the main portions of the shaft, said crank portions spaced in the direction of length of the shaft for grasp of each crank portion by a different hand of the person, a pair of propulsion instrumentalities each incorporating a hub-structure and a plurality of outwardly radiating oars carrying paddle formations at their outer ends, each of said instrumentalities being at a different one of the two sides of the boat and outboard relative thereto, a pair of clutches each having the two complementary members thereof on said shaft outboard relative to the hub-structure at that side of the boat, in each clutch the inner one of said members being fixed relative to the adjacent hub-structure, means rotatively connecting the outer member of each clutch to the shaft for rotation therewith and also for endwise movement with said shaft relative to its respective inner clutch member, and a plurality of springs for normally maintaining the members of both clutches in engagement to render both clutches normally effective, said shaft being axially movable for disabling the clutch at the starboard or port side of the boat and at the same time permitting the clutch at the other side of the boat to remain effective, said bearings being removably secured to the top of the boat's hull at opposite sides of the boat, each of said bearings rotatively carrying one of said hub-structures.

6. A manually operable propulsion and steering mechanism for a boat having a seat for a person to operate said mechanism, said mechanism comprising a transverse shaft, bearings for securing to the boat at opposite sides thereof and supporting said shaft to be moved axially, the shaft having near the middle point of its length a pair of crank portions oppositely offset from the general line of extension of the main portions of the shaft, said crank portions spaced in the direction of length of the shaft for grasp of each crank portion by a different hand of the person, a pair of propulsion instrumentalities each incorporating a hub-structure and a plurality of outwardly radiating oars carrying paddle formations at their outer ends, each of said instrumentalities being at a different one of the two sides of the boat and outboard relative thereto, a pair of clutches each having the two complementary members thereof on said shaft outboard relative to the hub-structure at that side of the boat, in each clutch the inner one of said members being fixed relative to the adjacent hub-structure, means rotatively connecting the outer member of each clutch to the shaft for rotation therewith and also for endwise movement with said shaft relative to its respective inner clutch member, a plurality of springs for normally maintaining the members of both clutches in engagement to render both clutches normally effective, said shaft being axially movable for disabling the clutch at the starboard or port side of the boat and at the same time permitting the clutch at the other side of the boat to remain effective, and means including a pair of elements

each fixed on the shaft near a different end thereof at a point inboard relative to said hub-structures for moving said shaft to a centrally located position with relation to said bearings, said last-named means further including, for coaction with each of said elements, a pivotally mounted equalizing lever, and springs acting on each of said levers, said last-named springs being arranged individually to yield according as the shaft is endwisely moved in one direction or the other, the first named springs including a pair of like springs and the second-named springs including a pair of like springs.

7. A manually operable propulsion and steering mechanism for a boat having a seat for a person to operate said mechanism, said mechanism comprising a transverse shaft, bearings for securing to the boat at opposite sides thereof and supporting said shaft to be moved axially, the shaft having near the middle point of its length a pair of crank portions oppositely offset from the general line of extension of the main portions of the shaft, said crank portions spaced in the direction of length of the shaft for grasp of each crank portion by a different hand of the person, a pair of propulsion instrumentalities each incorporating a hub-structure and a plurality of outwardly radiating oars carrying paddle formations at their outer ends, each of said instrumentalities being at a different one of the two sides of the boat and outboard relative thereto, a pair of clutches each having the two complementary members thereof on said shaft outboard relative to the hub-structure at that side of the boat, in each clutch the inner one of said members being fixed relative to the adjacent hub-structure, means rotatively connecting the outer member of each clutch to the shaft for rotation therewith and also for endwise movement with said shaft relative to its respective inner clutch member, a plurality of springs for normally maintaining the members of both clutches in engagement to render both clutches normally effective, said shaft being axially movable for disabling the clutch at the starboard or port side of the boat and at the same time permitting the clutch at the other side of the boat to remain effective, and means including a pair of elements each fixed on the shaft near a different end thereof at a point inboard relative to said hub-structures for moving said shaft to a centrally located position with relation to said bearings, said last-named means further including, for coaction with each of said elements a pivotally mounted equalizing lever, and springs acting on each of said levers, said last-named springs being arranged individually to yield according as the shaft is endwisely moved in one direction or the other, the first-named springs including a pair of like springs and the second-named springs including a pair of like springs, one of said pairs of springs being expansion springs.

8. A manually operable propulsion and steering mechanism for a boat having a seat for a person to operate said mechanism, said mechanism comprising a transverse shaft, bearings for securing to the boat at opposite sides thereof and supporting said shaft to be moved axially, the shaft having near the middle point of its length a pair of crank portions oppositely offset from the general line of extension of the main portions of the shaft, said crank portions spaced in the direction of length of the shaft for grasp of each crank portion by a different hand of the person, a pair of propulsion instrumen-

talities each incorporating a hub-structure and a plurality of outwardly radiating oars carrying paddle formations at their outer ends, each of said instrumentalities being at a different one of the two sides of the boat and outboard relative thereto, a pair of clutches each having the two complementary members thereof on said shaft outboard relative to the hub-structure at that side of the boat, in each clutch the inner one of said members being fixed relative to the adjacent hub-structure, means rotatively connecting the outer member of each clutch to the shaft for rotation therewith and also for endwise movement with said shaft relative to its respective inner clutch member, a plurality of springs for normally maintaining the members of both clutches in engagement to render both clutches normally effective, said shaft being axially movable for disabling the clutch at the starboard or port side of the boat and at the same time permitting the clutch at the other side of the boat to remain effective, and means including a pair of elements each fixed on the shaft near a different end thereof at a point inboard relative to said hub-structures for moving said shaft to a centrally located position with relation to said bearings, said last-named means further including, for coaction with each of said elements a pivotally mounted equalizing lever, and springs acting on each of said levers, said last-named springs being arranged individually to yield according as the shaft is endwisely moved in one direction or the other, the first-named springs including a pair of like springs and the second-named springs including a pair of like springs, one of said pairs of springs being expansion springs, and the other pair thereof being contraction springs.

9. In combination with a boat having opposed gunwales, bearings removably mounted on the gunwales, tubular hubs rotatably and removably mounted in said bearings in end alignment, oars extending radially from said hubs, a crank shaft having its ends rotatively and slidably extended through and beyond said hubs, clutch teeth formed on the outer faces of said hubs, clutch discs rotatively and slidably mounted on the outer ends of said shaft and having clutch teeth arranged to engage the clutch teeth of said hub, tubular housings engaged over the free ends of said shaft and having their outer ends closed and their inner ends engaged over said clutch discs, means non-rotatively and non-slidably connecting said tubular housings to said shaft, means slidably but non-rotatively connecting said clutch discs to said housings, and a spring within each of said housings operating between the closed ends thereof and the adjacent ends of said clutch discs urging said clutch discs into a position in which said clutch teeth of said clutch discs will be engaged with the clutch teeth of said hubs.

10. In combination with a boat having opposed gunwales, bearings removably mounted on the gunwales, tubular hubs rotatably and removably mounted in said bearings in end alignment, oars extending radially from said hubs, a crank shaft having its ends rotatively and slidably extended through and beyond said hubs, clutch teeth formed on the outer faces of said hubs, clutch discs rotatively and slidably mounted on the outer ends of said shaft and having clutch teeth arranged to engage the clutch teeth of said hub, tubular housings engaged over the free ends of said shaft and having their outer ends closed and

their inner ends engaged over said clutch discs, means non-rotatively and non-slidably connecting said tubular housings to said shaft, means slidably but non-rotatively connecting said clutch discs to said housings, a spring within each of said housings operating between the closed ends thereof and the adjacent ends of said clutch discs urging said clutch discs into a position in which said clutch teeth of said clutch discs will be engaged with the clutch teeth of said hubs, said housings being formed of opposed sections having semi-circular end walls closing the said end thereof and engaging flat surfaces milled into the extended end of said shaft, and screws releasably connecting said sections together forming the means non-rotatively and non-slidably connecting said housings to said shaft.

11. In combination with a boat having opposed gunwales, bearings removably mounted on the gunwales, tubular hubs rotatably and removably mounted in said bearings in end alignment, oars extending radially from said hubs, a crank shaft having its ends rotatively and slidably extended through and beyond said hubs, clutch teeth formed on the outer faces of said hubs, clutch discs rotatively and slidably mounted on the outer ends of said shaft and having clutch teeth arranged to engage the clutch teeth of said hub, tubular housings engaged over the free ends of said shaft and having their outer ends closed and their inner ends engaged over said clutch discs, means non-rotatively and non-slidably connecting said tubular housings to said shaft, means slidably but non-rotatively connecting said clutch discs to said housings, a spring within each of said housings operating between the closed ends thereof and the adjacent ends of said clutch discs urging said clutch discs into a position in which said clutch teeth of said clutch discs will be engaged with the clutch teeth of said hubs, said housings being formed of opposed sections having semi-circular end walls closing the said end thereof and engaging flat surfaces milled into the extended end of said shaft, and screws releasably connecting said sections together forming the means non-rotatively and non-slidably connecting said housings to said shaft, said latter-mentioned means comprising pins extending from said clutch discs and engaging elongated slots formed in said housing and extended parallel to said shaft.

12. In combination with a boat having opposed gunwales, bearings removably mounted on the gunwales, tubular hubs rotatably and removably mounted in said bearings in end alignment, oars extending radially from said hubs, a crank shaft having its ends rotatively and slidably extended through and beyond said hubs, clutch teeth formed on the outer faces of said hubs, clutch discs rotatively and slidably mounted on the outer ends of said shaft and having clutch teeth

arranged to engage the clutch teeth of said hub, tubular housings engaged over the free ends of said shaft and having their outer ends closed and their inner ends engaged over said clutch discs, means non-rotatively and non-slidably connecting said tubular housings to said shaft, means slidably but non-rotatively connecting said clutch discs to said housings, and a spring within each of said housings operating between the closed ends thereof and the adjacent ends of said clutch discs urging said clutch discs into a position in which said clutch teeth of said clutch discs will be engaged with the clutch teeth of said hubs, said housings being of one-piece construction, said first-mentioned means comprising set screws threaded through the closed end of said housings and tightened against the end of the shaft.

13. In combination with a boat having opposed gunwales, bearings removably mounted on the gunwales, tubular hubs rotatably and removably mounted in said bearings in end alignment, oars extending radially from said hubs, a crank shaft having its ends rotatively and slidably extended through and beyond said hubs, clutch teeth formed on the outer faces of said hubs, clutch discs rotatively and slidably mounted on the outer ends of said shaft and having clutch teeth arranged to engage the clutch teeth of said hub, tubular housings engaged over the free ends of said shaft and having their outer ends closed and their inner ends engaged over said clutch discs, means non-rotatively and non-slidably connecting said tubular housings to said shaft, means slidably but non-rotatively connecting said clutch discs to said housings, and a spring within each of said housings operating between the closed ends thereof and the adjacent ends of said clutch discs urging said clutch discs into a position in which said clutch teeth of said clutch discs will be engaged with the clutch teeth of said hubs, said housings being of one-piece construction, said first-mentioned means comprising set screws threaded through the closed end of said housings and tightened against the end of the shaft, said housings being formed with slots extended parallel to said shaft, said latter-mentioned means comprising bolts extended through said slots and threaded into said clutch discs.

ANTHONY GRACI.
